UNITED STATES PATENT OFFICE.

ARTHUR J. SAVAGE, OF CHICOPEE FALLS, MASSACHUSETTS, ASSIGNOR TO J. STEVENS ARMS & TOOL COMPANY, OF CHICOPEE FALLS, MASSACHUSETTS.

MAGAZINE-FIREARM.

No. 910,236.

Specification of Letters Patent.

Patented Jan. 19, 1909.

Application filed August 3, 1906. Serial No. 329,014.

To all whom it may concern:

Be it known that I, ARTHUR J. SAVAGE, a resident of Chicopee Falls, in the county of Hampden and State of Massachusetts, have 5 invented certain new and useful Improvements in Magazine-Firearms; and I do hereby declare that the following is a full, clear, and exact description thereof, which will enable others skilled in the art to which it applies 10 to make and use the same, reference being had to the accompanying drawings, and to the letters of reference marked thereon, which form a part of this specification.

The object of my present invention is to 15 provide a firearm of few and simple parts whereby the cost of construction is reduced to a minimum and in which efficiency is not sacrificed and several desirable features introduced.

20 Figure 1 shows a longitudinal sectional view of the frame and adjacent portions of fire arm of my improved construction with the breech open. Fig. 2 shows the same with the breech closed. Fig. 3 is a cross section taken on line A A of Fig. 2. Fig. 4 is a partial longitudinal section with the breech partially closed. Fig. 5 is a detail view of portions of the carrier. Fig. 6 is a cross section taken on line B B of Fig. 5. Fig. 7 is a 25 detail view of the breech bolt from the underside. Fig. 8 is a detail view of the firing pin, spring, etc. Fig. 9 is a cross sectional view of the bolt taken on line C C of Fig. 7.

Referring to the reference letters and figures in a more particular description, 1 indicates the frame which is a piece of general tubular form and receives the breech bolt 2 which is of general cylindrical form, and also receives at its forward end the rear end of the 30 barrel 3. At the forward end the receiver 1 is provided with a depending lug 4 preferably screw threaded into the under forward portion thereof and providing a support for the rear end of the magazine 5, and also adapted 35 to receive the frame screw 6 by means of which the stock 7 is secured to the barrel and frame. The rear end of the barrel in arms of small caliber may be inserted into the forward end of the frame without screw threading, as indicated at 8 and secured in position 40 by the point 9 of the stud 4 before mentioned, the said stud being screw threaded into the receiver. At the rear portion and on the underside the receiver 1 also carries a

55 screw threaded stud 10 in which is pivoted the combination carrier and trigger 11. This piece 11 is in the main a thin plate piece adapted to be stamped out and carries at its forward end the cartridge receiving socket 12, which socket is preferably a separate 60 piece straddling the forward end of the part 11 and secured thereto by a pin 13.

In connection with the forward end of the combination trigger and cartridge carrier and the socket piece 12 thereof, there is provided a reciprocating cartridge pusher 14 having a tooth as shown adapted to engage the head of the cartridge and extending longitudinally in the piece 11, and adapted to be engaged by the forward end of the breech 65 bolt. The rear end of the breech bolt is provided with a handle 15 by means of which it is both rotated and reciprocated, and the base of the handle 15 is adapted to engage in a notch or recess 16 in the rear end of the 70 frame whereby the bolt is locked against longitudinal movement when in firing position. Within the bolt there is mounted the firing pin 17 which has at its forward end the striking pin 18 adapted to be projected through a 75 small opening in the forward practically solid end of the breech bolt and reach the cartridge when in position in the barrel. The firing pin is retained in the breech bolt by a pin 19 passing transversely through the bolt 80 and through a slotted opening 20 in the firing pin. The rear end of the firing pin is provided with a knob or head 21 by means of which the operator may handle the firing pin. The forward end of the firing pin is 85 provided with a head 17^a, while adjacent to the rear end it is surrounded by a ring 22 and between the ring 22 and the head 17^a and around a reduced portion of the firing pin is provided the firing pin 90 spring 23. The ring 22 is retained in position in the breech bolt also by the pin 19, which passes through an enlarged opening in the ring 22 allowing a small amount of lateral movement of the ring 22 with reference to 95 the pin 19. The rear end of the ring 22 is adapted to engage with a shoulder on the rear end of the firing pin so that when not in firing position the spring 23 is confined between the head 17^a on the one hand and 100 practically the shoulder on the rear end of the firing pin on the other. When in cocked position the spring is confined between the 105

head 17^a on the forward end of the firing pin and the cross pin 19 at the rear end. At a suitable point on the circumference and at the rear end the breech bolt is cut away to afford clearance for the sear 25 to reach the firing pin, and the firing pin is provided with a shoulder 26 with which the sear is adapted to engage. The sear 25 is a short lever pivoted in the frame and is adapted to be engaged at the forward end by a shoulder 11^a on the combination trigger and carrier 11, and the sear is operated to engaging position with the firing pin and the trigger and sear operated also by a spring 28 interposed between the sear and the rear end of the part 11, and preferably coiled around a pin for better maintaining it in position. The forward end of the breech bolt will be provided with a cartridge extractor 29 in the usual manner.

In operation the forward end of the carrier is adapted to be dropped down into a position opposite the rear end of the magazine 5 and when in such lower position to receive a cartridge from the rear end of the magazine, the cartridge being forced rearward into the carrier by the usual spring in the magazine. When the breech bolt is open the carrier is adapted to rise to bring the cartridge socket 30 into line with the rear end of the barrel and is caused to move to this position, both by the spring 28 and the shoulder on the forward side of the projection 11^b, engaging with a shoulder on the forward end of the breech bolt. In an early part of the forward movement of the breech bolt the same engages with a cartridge pusher 14 and moves the cartridge out of the carrier socket into the rear end of the barrel. The arrangement is such that when the cartridge has partially entered the barrel, sufficiently so to become supported thereby and has passed out of the forward end of the carrier socket, the shoulder 30 on the underside of the breech bolt 45 will come into engagement with the projection 11^b and move the carrier down. This operation is sufficient to allow the forward end of the breech bolt to pass over the rear end of the socket piece 12 in its movement 50 towards the rear end of the barrel. As the breech bolt is moved towards closed position the firing pin is caught by the sear 25 and held back, thereby cocking the firing pin and the shoulder 11^a is brought up into close relation with the forward end of the sear. When the breech bolt is entirely closed and locked, there will be brought into position directly over the carrier-trigger piece projection 11^c a pocket or recess 2^a in the under- 55 side of the breech bolt, which the projection 11^c is adapted to enter, and at other times this projection 11^c is adapted to strike the side of the breech bolt and block the movement of the trigger, serving as a safety appliance. When the trigger is pulled by the op-

erator it engages with and releases the sear from the firing pin, at the same time the forward end of the trigger-carrier part has a slight downward movement, there being sufficient clearance provided in the frame for this additional movement of the carrier part when the trigger is being operated as a trigger.

In case it is desired to close the breech bolt without having a cartridge in the barrel the carrier can be moved down by means of the trigger as the breech bolt is being closed and avoid delivering a cartridge into the barrel. In opening the breech after firing the spent shell is drawn out by the extractor 29 at the forward end of the breech bolt 2, and as the carrier rises the shell is flipped out of the opening O in the top of the frame.

When the cartridges in the magazine are exhausted the arm can be operated as a single loader, cartridges being introduced through the opening O into the rear end of the barrel, the carrier being moved down out of the way by pressure on the trigger or pressure on the socket piece 12.

What I claim as new and desire to secure by Letters Patent is:

1. The combination, in a fire arm, with the frame, barrel, magazine, and breech bolt, of a part constituting a trigger and a cartridge carrier and having a socket-piece for receiving cartridges, and a breech bolt having a cam shoulder adapted to engage with the said carrier and depress the same to allow the said breech bolt to pass over the said socket piece, substantially as set forth.

2. The combination in a fire arm of a barrel, magazine, breech bolt, carrier having a socket adapted to be moved to register with the magazine and with the barrel, and a cartridge pusher consisting of a sliding bar located in a longitudinal groove in the lower wall of the socket and having a tooth projecting into the socket, said pusher arranged to be engaged to the rear of the socket by the breech bolt, substantially as set forth.

3. The combination, in a fire arm, of a swinging part constituting a cartridge carrier and trigger, a pivoted sear located at the rear of the pivot of the said swinging part and movable independently thereof, said swinging part being provided with a shoulder to engage said sear, a spring-pressed firing-pin having a shoulder to be engaged by said sear, a sliding breech-bolt having a cam shoulder to engage said carrier and depress the same when said breech-bolt is moved forward, and a sliding cartridge pusher mounted on said carrier and arranged to be engaged by said breech-bolt.

4. The combination, in a fire arm, of a swinging part constituting a carrier and trigger, a sear located rearward of the pivot of the said swinging part and pivoted in the frame for independent movement, said

125

130

swinging part being provided with a shoulder arranged to engage said sear, a single spring acting on said sear and said swinging carrier-trigger part, and permitting independent movements of the latter and of said sear, a firing-pin having a shoulder to be engaged by said sear, a sliding breech-bolt, and a sliding cartridge pusher mounted on said carrier and arranged to be engaged by said

breech bolt when the latter is moved forward.

In witness whereof, I have affixed my signature, in presence of two witnesses, this 31st day of July, 1906.

ARTHUR J. SAVAGE.
